(57) **CLAIM**

The ornamental design for a wheel well closeout as shown
and described.

DESCRIPTION

FIG. 1 depicts a front view of a wheel well closeout showing
our new design according to a first embodiment.

FIG. 2 depicts a back view thereof.

FIG. 3 depicts a bottom view thereof.

FIG. 4 depicts a top view thereof.

FIG. 5 depicts a left side view thereof.

FIG. 6 depicts a right side view thereof.

FIG. 7 depicts a front, top, left perspective view thereof.

FIG. 8 depicts a front, bottom, right perspective view
thereof.

FIG. 9 depicts a front view of a wheel well closeout showing
our new design according to a second embodiment.

FIG. 10 depicts a back view thereof.

FIG. 11 depicts a bottom view thereof.

FIG. 12 depicts a top view thereof.

FIG. 13 depicts a left side view thereof.

FIG. 14 depicts a right side view thereof.

FIG. 15 depicts a front, top, left perspective view thereof;
and,

FIG. 16 depicts a front, bottom, right perspective view
thereof.

The dot-dash lines depict boundaries of the claimed design.
The even dash lines depict portions of the article forming no
part of the claimed design.

1 Claim, 16 Drawing Sheets
